CONVERTING HYDROCARBON OILS

Richard F. Trow, Port Arthur, Tex., assignor to
The Texas Company, New York, N. Y., a corporation of Delaware

Application May 19, 1931, Serial No. 538,592

5 Claims. (Cl. 196—58)

This invention relates to the conversion of higher boiling hydrocarbon oils into lower boiling ones and relates particularly to selectively separating a charge oil, by distillation, and converting the separated portions under varying cracking conditions to produce a high yield of motor fuel having high anti-knock qualities and a minimum yield of residue and gas.

According to the invention a charge oil, such as an unclean gas oil, is contacted with hot cracked vapors produced in the process by which the more volatile portion of the charge oil is vaporized and the heaviest least refractory portion is cracked and partially vaporized while a portion of the vapors is condensed and deposited along with a remaining unvaporized portion of the charge oils. The combined vapor is scrubbed in the distillation zone and is then dephlegmated to produce a final motor fuel vapor and a clean gas oil condensate which is heated to a temperature well above the usual cracking temperature for such a stock. The residual cooler portion from the distillation zone is combined with the heated products from the heater and the mixture is subjected to an appropriate time of digest in enlarged zones. The resultant hot vapors are delivered to the distillation zone to effect distillation of the charge oil and a residue, being deposited in the digestion zones, is subjected to autogenous distillation to produce an ultimate residue and a vaporous portion which is preferably condensed and delivered to the cracked vapor dephlegmating means.

The various advantages and objects of my invention will be apparent from the following description taken in connection with the accompanying drawing which illustrates diagrammatically a preferred embodiment of apparatus suitable for practicing the process.

Element 1 is a heater, 2 and 3 are reaction vessels, 4 is a combination reaction vessel, distillation tower and scrubber. 5 is a flash distillation vessel, 6 is a dephlegmator, 7 is a reflux condenser, 8 is a final condenser and 9 is an accumulator vessel.

A pipe 15 conveys fresh charge oil thru a coil 16 and optionally thru a coil 17 into the vessel 4. A vapor line 20 connects the top of the vessel 4 with the lower portion of the dephlegmator 6. A vapor line 21 and a run back line 22 connect the upper portion of the dephlegmator with the lower portion of the reflux condenser 7. A final vapor line 23 leads to the final condenser 8 and a line 24 leads from the condenser to the accumulator 9 which has a liquid outlet 25 and a gas outlet 26.

A pump 31 takes suction thru a line 30, from the bottom of the dephlegmator and discharges thru a line 32 into the heater 1. A transfer line 33 connects the heater with the upper portion

of the vessel 2 and lines 34 and 35 connect the vessels 2 and 3, and 3 and 4 respectively.

Drawoff lines 40 and 41 from vessels 2 and 3, respectively, lead into a manifold line 43 which is connected to the lower portion of the vessel 5. A draw-off line 44 leads from the bottom of the vessel 4 to a pump 45 which discharges thru a line 46 into the transfer line 33. A discharge line 47 from the vessel 5 leads to storage or other means not shown. Jump over lines 48 and 49 are provided leading into the discharge line 47.

In order to furnish cooling to the several vessels in which scrubbing and fractionation is carried on return lines are provided to return a cooling liquid. In some cases where the desirable reflux medium may be so warm as to require considerable quantities of it cooling coils are provided to reduce the amount of cooling medium to be pumped back.

A branch line 65 is provided from the line 32 by which a portion of the clean gas oil may be pumped back thru a cooler 66 into the upper portion of the vessel 4. Another branch line 70 is provided from the line 32 thru a cooler 71 to the baffles in the dephlegmator 6.

A connection from the condensate discharge from the pump 61 is provided to the upper portion of the vessel 5.

Another connecting line 75 together with a pump 76 is provided for pumping a trapped out portion of the final condensate back to the reflux condenser 7.

When beginning to operate, a sufficient amount of clean oil may be drawn thru a line 29 from a source not shown and pumped into the heater 1. After operating conditions are established, a switch may be made to the fresh charge oil which is drawn in thru the line 15.

In a preferred mode of operation a gas oil of say 25° Bé. gravity may be charged to a baffle plate in the upper portion of the vessel 4 where it is contacted with rising hot cracked vapor from the cracking zone. A virgin gas oil fraction of this gravity obtained from the distillation of crude petroleum will usually contain some heavy constituents which will cause the distillation temperature to rise sharply when distilling it at atmospheric pressure.

The heavier constituents of the gas oil being the most refractory constitute the portion of a fresh charge which decomposes most readily to form pitch or coke and gas and while it would not be practicable to subject this portion to the high temperatures at which the high anti-knock motor fuel is produced it is possible to subject it to milder conditions and decompose it into a somewhat lighter product the major portion of which would be a lighter more refractory gas oil which could be subjected to the high temperature.

Thus as the charge oil delivered into the vessel 60

4 spreads out over the baffles and is moved downwardly in countercurrent to the hot cracked vapor the lighter portion, which may comprise 90 to 95 percent of the charge oil, is vaporized. The 5 remainder as it moves downwardly in the column, coming in contact with the hot cracked vapors introduced near the bottom of the column, is heated to such a temperature that a substantial portion of it is decomposed into lighter products 10 and some tarry substances at the higher temperature during the time of downward movement. The resultant lighter products are vaporized and combined with the other vapor while the tarry substance is precipitated in the bottom of the 15 vessel together with any residue which may be precipitated from the hot cracked vapor.

The total vapor in the vessel 4 is subjected to a scrubbing step in the top of the vessel, without substantial cooling, to remove such tarry and 20 heavy liquid particles as might have become entrained therewith. Such substance as this it is known will decompose rapidly into coke particles which adhere readily to the heater tubes with deleterious effect. Thus it is desirable that the 25 vapor withdrawn overhead from the vessel 4 contain only a rather highly refractory clean gas oil fraction which has a relatively flat distillation curve toward the end.

The vapor is delivered into the dephlegmator 30 in which it undergoes conventional fractionation to produce an overhead vaporous motor fuel and a clean gas oil condensate.

The condensate is removed continuously almost as soon as it is deposited and charged to the 35 heater, only enough being held in the dephlegmator to insure a liquid seal and smooth regular operating conditions. The temperature is raised in the heater to approximately 960° F. at which the clean oil is substantially all vapor at the 40 pressure employed which is preferably about 400 pounds per square inch at the outlet.

It is to be understood that the residual portion 45 of the virgin charge deposited in the vessel 4 does contain some slight amount of constituents which may be further decomposed under more favorable conditions. As this residual portion is somewhat cooler than the highly heated gas oil it is of advantage to commingle the two for while it is necessary to heat the residual portion to effect 50 its further decomposition it is also desirable to quench the highly heated oil to prevent its further decomposition into coke and gas. By combining the two an average temperature of say 900° F. in the transfer line 32 is attained.

55 The combined oil and vapor is delivered into the upper portion of the first reaction vessel 2 where additional quantities of liquid are vaporized and some of the remaining liquid portion is also atomized, and passed into the vessel 3. The 60 vapor finally emerging from the top of the vessel 3 is delivered under considerably reduced pressure, e. g. 150 pounds per square inch, into the vessel 4. Thus after a desirable time of digest in the vessels 2 and 3 where an appropriate temperature is maintained to effect conversion of the 65 combined vapor and mist particles the reaction is stopped by reducing the pressure and temperature simultaneously upon discharging into the vessel 4.

70 The cracked vapor, at the reduced temperature, furnishes a heating medium for the fresh charge being delivered into the vessel 4 which is hot enough to vaporize the lighter and crack and 75 vaporize the heavier portion as previously described.

The residue which is deposited in the vessel 2 and 3 is almost immediately withdrawn and is delivered into an autogenous distillation zone of considerably reduced pressure, e. g. 10 pounds per square inch more or less, where the remaining 5 gas oil fraction is flashed off and the final residue is discharged from the system. The residue as it is precipitated in the reaction vessels 2 and 3 will contain some small amount of gasoline fraction as well as gas oil altho the preponderance 10 of the material distillate in the autogenous distillation step will be the latter. The vapor developed in this step is scrubbed in the upper portion of this vessel to remove all traces of tarry and coke substance. The clean vapor is then passed 15 thru a condenser 60 from which a pump 61 takes suction and discharges the entire condensate to the uppermost of a series of baffles into the dephlegmator 6. Here the condensate is fractionated, along with the vapors entering thru the 20 pipe 28, to produce motor fuel as vapor leaving the top of the tower 6 and a cracking stock as condensate collecting at the bottom of the tower.

The total combined vapor from the dephlegmator 6 is subjected to additional condensation in 25 the reflux condenser 7 and a final overhead vapor is condensed in the condenser 8. As there will be a small amount of non-condensable gas developed in the cracking it is preferable to pass the products from the condenser 8 into an accumulator 30 in which the gas and liquid are separated and each is discharged to further means thru their respective outlet lines.

While I have described a preferred mode of operation it is to be understood that no limitation 35 is thus intended to the scope of my invention which is to be limited only by the appended claims.

What I claim is:

1. The process of converting higher boiling 40 hydrocarbon oils into lower boiling ones that comprises introducing charging stock to a columnar distillation zone maintained under superatmospheric pressure and fed with vapors at high cracking temperature from an enlarged 45 cracking zone to thereby dephlegmorate the vapors and to subject the charging stock to vaporization to vaporize portions thereof adapted for cracking at high temperatures and to subject unvaporized portions of the charging stock to 50 cracking temperatures to effect cracking with the formation of an ultimate residual oil maintained at cracking temperature and an overhead vapor fraction comprising vaporized components of the charging stock as well as cracked constituents, subjecting the overhead vapor fraction to fractionation to form a final light distillate and a gas oil condensate, passing said gas oil condensate through a heating coil wherein the condensate oil is subjected to a high cracking 55 temperature to effect a high rate of cracking, combining residual oil withdrawn from the columnar distillation zone with the highly heated products from said heating coil and directing the combined products into an enlarged cracking 60 zone wherein separation of vapors from liquid occurs and wherein cracking temperature under a superatmospheric pressure materially higher than that of said columnar distillation zone is maintained and from which the separated vapors 65 are expanded into said columnar distillation zone, and withdrawing liquid from said enlarged zone at a rate adequate to prevent accumulation of liquid therein without conducting any of the residual oil to said heating coil.

2. The process of converting higher boiling hydrocarbon oils into lower boiling ones that comprises introducing charging stock to a columnar distillation zone maintained under superatmospheric pressure and fed with vapors at high cracking temperature from an enlarged cracking zone to thereby dephlegmate the vapors and to subject the charging stock to vaporization to vaporize portions thereof adapted for cracking at high temperatures and to subject unvaporized portions of the charging stock to cracking temperatures to effect cracking with the formation of an ultimate residual oil maintained at cracking temperature and an overhead vapor fraction comprising vaporized components of the charging stock as well as cracked constituents, subjecting the overhead vapor fraction to fractionation to form a final light distillate and a gas oil condensate, passing said gas oil condensate through a heating coil wherein the condensate oil is subjected to a high cracking temperature to effect a high rate of cracking, combining residual oil withdrawn from the columnar distillation zone with the highly heated products from said heating coil and directing the combined products into an enlarged cracking zone wherein separation of vapors from liquid occurs and wherein cracking temperature under a superatmospheric pressure of upwards of 400 pounds and materially higher than that of said columnar distillation zone is maintained and from which the separated vapors are expanded into said columnar distillation zone, and withdrawing liquid from said enlarged zone at a rate adequate to prevent accumulation of liquid therein without conducting any of the residual oil to said heating coil.

3. The process of converting higher boiling hydrocarbon oils into lower boiling ones that comprises introducing charging stock to a columnar distillation zone maintained under superatmospheric pressure and fed with vapors at high cracking temperature from an enlarged cracking zone to thereby dephlegmate the vapors and to subject the charging stock at first to vaporization to vaporize portions thereof adapted for cracking at high temperatures and finally to subject unvaporized portions of the charging stock to increased temperatures to effect cracking with the formation of an ultimate residual oil maintained at cracking temperature and an overhead vapor fraction comprising vaporized components of the charging stock as well as cracked constituents, subjecting the overhead vapor fraction to fractionation without any material reduction in pressure to form a final light distillate and a gas oil condensate adapted to be completely vaporized without the formation of coke, passing said gas oil condensate in a stream through a heating coil to subject the oil to cracking in the vapor phase, combining residual oil withdrawn from the columnar distillation zone with the highly heated products from said heating coil and directing the combined products into an enlarged cracking zone wherein separation of vapors from liquid occurs and wherein cracking temperature under a superatmospheric pressure materially higher than that of said columnar distillation zone is maintained and from which the separated vapors are expanded into said columnar distillation zone, withdrawing liquid from said enlarged zone at a rate adequate to prevent accumulation

tion of liquid therein, without conducting any residual oil to said heating coil expanding the residual oil thus withdrawn into an auto-distillation zone maintained under a materially lower pressure than that of said columnar distillation zone, obtaining a condensate from the resultant vapors and subjecting the condensate to fractionation at increased pressure with the vapors from the columnar distillation zone.

4. A hydrocarbon oil cracking process which comprises passing a relatively light and clean distillate, formed as hereinafter set forth, through a heating zone and heating the same therein to cracking temperature under pressure, discharging the heated distillate into a reaction zone maintained under cracking conditions of temperature and pressure, removing vapors from the reaction zone and subjecting the same to primary dephlegmation in direct contact with fresh charging oil for the process, introducing the resultant mixture of unvaporized charging oil and primary reflux condensate, without passage through said heating zone and without prior heating to cracking temperature, directly into the reaction zone and commingling the same with the heated distillate therein, removing unvaporized oil from the reaction zone and flash distilling the same by pressure reduction, combining the vapors uncondensed by the primary dephlegmation with overhead products from the flash distillation in a secondary dephlegmation zone out of direct contact with charging oil thereby forming a secondary reflux condensate unadmixed with heavy oil, supplying the secondary reflux condensate, unadmixed with fresh charging oil, to the heating zone as said relatively light and clean distillate, and finally condensing as a product of the process the vapors uncondensed by the secondary dephlegmation.

5. A hydrocarbon oil cracking process which comprises passing a relatively light and clean distillate, formed as hereinafter set forth, through a heating zone and heating the same therein to cracking temperature under pressure, discharging the heated distillate into a reaction zone maintained under cracking conditions of temperature and pressure, removing vapors from the reaction zone and subjecting the same to primary dephlegmation in direct contact with fresh charging oil for the process, introducing the resultant mixture of unvaporized charging oil and primary reflux condensate directly into contact with the heated distillate discharged from said heating zone so that the heated distillate and mixture of unvaporized charging oil and primary reflux condensate are in contact at a cracking temperature in said reaction zone, removing unvaporized oil from the reaction zone at a rate adequate to prevent the accumulation of liquid therein and flash distilling the same by pressure reduction, combining the vapors uncondensed by the primary dephlegmation with overhead products from the flash distillation in a secondary dephlegmation zone out of direct contact with charging oil thereby forming a secondary reflux condensate unadmixed with heavy oil, supplying the secondary reflux condensate, unadmixed with fresh charging oil, to the heating zone as said relatively light and clean distillate and finally condensing as a product of the process the vapors uncondensed by the secondary dephlegmation.

RICHARD F. TROW.
